UNITED STATES PATENT OFFICE.

JACOB BINNIG, OF BOSTON, MASSACHUSETTS, ASSIGNOR OF ONE-HALF TO MASON & HAMLIN COMPANY, OF CAMBRIDGE, MASSACHUSETTS, A CORPORATION OF DELAWARE.

TRACKER-BOARD.

No. 858,782.

Specification of Letters Patent.

Patented July 2, 1907.

Application filed March 19, 1906. Serial No. 306,928.

To all whom it may concern:

Be it known that I, JACOB BINNIG, a citizen of the United States, residing at Boston, county of Suffolk, and State of Massachusetts, have invented an Improvement in Tracker-Boards, of which the following description, in connection with the accompanying drawings, is a specification, like letters on the drawings representing like parts.

This invention relates to tracker-boards, and has for its object to provide a novel construction of tracker-board which is well adapted to be made of metal (although the invention is not limited to a metal tracker-board), and in which the apertures can be arranged very compactly, thus permitting a certain number of apertures to be placed in a less space than is possible with tracker-boards as commonly made.

Some embodiments of my invention will first be described and then the novel features thereof pointed out in the appended claims.

20 In the drawings which show one embodiment of my invention, Figure 1 is a top plan view of a tracker-board constructed according to my invention, a part thereof being broken out; Fig. 2 is a section on the line *a—a*, Fig. 1; Fig. 3 is a view of the tracker-board partly in plan, partly on the line *y—y*, Fig. 2, and partly on the line *x—x*, Fig. 2; Fig. 4 is a top plan view of a portion of one of the side pieces of the tracker-board after it has been slotted for the reception of the partitions; Fig. 5 is a section on the line *b—b*, Fig. 4; Fig. 6 is a section on the line *c—c*, Fig. 4; Fig. 7 shows a different way of constructing a tracker-board embodying my invention, and Fig. 8 is a detail of a spacing-block.

The tracker-board herein shown is formed of an upper and a lower section. The upper section has there-in the ducts or apertures 3 through the top of the tracker-board which communicate with the perforations in the perforated music sheet, and said upper section also has a transversely-extending chamber 4 communicating with each duct. The lower section has a plurality of rows of ducts 5 having a staggered arrangement, one duct for each of the transversely-extending chambers. The upper section may be made in various ways, and in Figs. 1 to 6 I have shown it as comprising two side pieces 7 and 8, each chambered out on its inner side, as at 9, see Fig. 5, with the chambers 9 extending substantially the full length of the side pieces. When thus made, each side piece has the vertical side portion 10 and the horizontally-extending top flange 11. Each side piece is then provided with a plurality of slits 12, see Fig. 4, which extend from the inner edge 13 thereof toward the outer edge to a point beyond the wall of the chamber 9, or to substantially the line 14 in Figs. 5 and 6. After each side piece 7 and 8 has thus been chambered and slotted, they are placed together

with the slotted sides toward each other, as shown in Fig. 1, and with the slits in alinement, the spacing-blocks or bars 23 having been previously placed between them at their ends. Thin plates 15 are inserted in the alined slits, said plates 15 dividing the chamber into the transversely-extending chambers 4 above referred to. These partitions 15 come flush with the upper surface of the tracker-board, and may be secured in place by soldering or in any other suitable way. Said partitions 15, therefore, not only sub-divide the chambers 9 into the chambers 4, but they also form with the top portions 11 of the separated side pieces the apertures 3. The dimension of each aperture 3 transversely of the tracker-board depends on the thickness of the filling pieces 23, while the dimension in the direction longitudinally of the tracker-board depends on the distance between the partitions 15. As herein shown, the bottom edges of said partitions come flush with the bottom edges of the side pieces 7 and 8.

The ducts or conduits 5 are secured to a base-piece 18 which is removably secured to the side pieces 7 and 8, preferably by means of screws 40. Said base-piece is provided with a plurality of apertures or ports 19 which register with the conduits 5. These ports 19 are so arranged that one port communicates with each of the chambers 4, as clearly seen in Fig. 3, and because the chambers 4 extend transversely of the tracker-board, it is possible to arrange the ports 19 and consequently the conduits 5 in a plurality of longitudinal rows.

In Fig. 7, I have shown another way of constructing a tracker-board embodying my invention. In this embodiment, the body of the tracker-board is made up of transversely-extending partitions 15' which extend clear from one end to the other, and spacing-blocks 69 situated between adjacent partitions, each spacing-block having substantially the shape shown in Fig. 8. These spacing-blocks are so shaped that when they are assembled with the partitions 15', the transversely-extending chambers 4 are formed. These partitions and spacing-blocks may be secured together in any suitable way.

When the body of the tracker-board is made, said tracker-board is completed by detachably securing the base-piece 18 thereto, as above described.

In both of the forms of the invention herein illustrated, I propose to employ a packing-strip 65 of leather, felt or other similar material between the base-piece 18 and the body of the tracker-board, this packing-strip being employed for the purpose of making a tight joint at this point.

In the manufacture of the tracker-board after the body has been made, said body, the base-piece and packing-strip 65 are assembled and secured together, the base-piece having previously been formed with

the apertures or ports 19. The packing-strip 65 is then perforated in some suitable way, as, for instance, by inserting a hot needle or other tool through each of the ports 19. This will result in upsetting the edge of the packing-strip adjacent each aperture therein, as at 64 (see Fig. 2). The advantage of this construction will be pointed out later.

I have herein shown the apertures 3 through the top of the tracker-board as having the flaring sides 20. I give the apertures this shape so as to facilitate as much as possible the entrance of air into the chambers 4 through said apertures.

An advantage is gained by making the passages through the tracker-board in the form shown, that is, with an aperture 3 leading to an enlarged chamber 4. In the first place, it permits the conduits 5 to be readily separated from each other sufficiently so that they will not interfere with each other, and in the second place, it furnishes a settling chamber within the tracker-board in which any dust or other fine particles of foreign matter which enter the apertures 3 may accumulate without being drawn into the ducts 5 which lead to the pneumatics.

The cross-sectional area of each chamber 4 is many times greater than the area of the aperture 3, and obviously, therefore, the air which is drawn in through the aperture 3 enters said aperture rapidly, yet when this volume of air reaches the settling chamber 4 it will have a comparatively slow movement sufficient to allow any dust or foreign matter thereon to settle, and the chances that such foreign matter will be drawn into the port 19 are very small. The bur is turned-up edge 64 which is formed in the packing material 65, as above described, forms a sort of guard around each of the ports 19 to prevent any dust from getting into said ports.

It will be noted that the base-piece 18 is detachably secured to the body of the tracker-board, and that when said base-piece is removed, the chambers 4 and ducts 5 are readily accessible for cleaning. I regard this feature as of considerable importance, because if

for any reason any of the chambers 4 or the ports 19 become clogged, they may be readily cleaned by removing the base-piece 18. With my improvement, therefore, there is little likelihood that the passages 45 through the tracker-board will become clogged, and if dust does accumulate in the chamber 4, it may be readily removed.

Having fully described my invention, what I claim as new and desire to secure by Letters Patent is:—

1. A tracker board having a plurality of transversely-extending chambers and an aperture leading to each chamber through the top of the tracker board, all the apertures being similar and each aperture having a varying diameter.

2. A tracker board having a plurality of transversely-extending chambers and an aperture leading to each chamber through the top of the tracker board, all the apertures being similar and each aperture having a larger diameter where it opens into the chamber than at the top surface of the tracker board.

3. A tracker board composed of an upper section and a separate lower section, said upper section having a longitudinally-extending chamber and a plurality of transversely-extending slits each extending from the upper surface of said section to the bottom thereof, and partitions in said slits sub-dividing the longitudinal chamber into transverse chambers, said lower section having ducts leading to the chambers.

4. A tracker-board composed of an upper section and a lower section, said upper section comprising two side pieces each shaped to present the side portion 10 and the horizontally-extending top portion 11, and each having a plurality of slits formed therein and partitions occupying said slits and extending from the top to the bottom of said section, and said lower section having a duct therein leading to the space between each partition.

5. A tracker - board comprising two chambered side pieces, each having transversely-extending slits or grooves, partitions inserted in said grooves and dividing the interior of the tracker-board into transversely-extending chambers, and a base piece provided with a port for each chamber.

In testimony whereof, I have signed my name to this specification, in the presence of two subscribing witnesses.

JACOB BINNIG.
